FILING PHILATELIC ENVELOPES AND THE
LIKE

Arthur C. Short, Jackson, Miss.

Application April 3, 1941, Serial No. 386,716

7 Claims. (Cl. 129—20)

The invention relates to filing and mounting envelopes and similar articles for display and preservation, and while not confined thereto is adapted particularly for mounting first covers, or rare covers of the type collected by philatelists, especially those provided with flaps.

It is desirable that such envelopes or covers be filed flat and at the same time be readily available for exhibition, and capable of frequent manipulation without impairment of their condition. It is also desirable that the surface of the envelopes, particularly the upper parts of surfaces on which the stamps and post marks, etc., are placed, be at all times exposed to view. The present invention provides a simple device for holding such material securely in position on each side of a sheet or card. The sheets may be adapted to be placed in a loose-leaf binder, thus allowing the mounted envelopes to be bound in a book or album which may be easily handled so that the envelopes may be readily filed, displayed and inspected without injury or handling of the actual envelopes themselves. Such a device may include a sheet provided with cords or the like for holding the displayed material.

The device may be made in various sizes and may be used for many purposes but for purposes of explaining the invention there is illustrated and described a sheet such as may be used for filing and mounting envelopes or covers.

In the accompanying drawings Figure 1 is a rear elevation of a sheet showing cords in position. Fig. 2 is a front elevation of the sheet of Fig. 1. Fig. 3 is a rear elevation of an optional form of sheet showing envelopes in place. Fig. 4 is a front elevation of Fig. 3 showing envelopes in place. Fig. 5 is a transverse vertical section on the line 5—5 of Fig. 3. Fig. 6 is a front elevation of another form of sheet. Fig. 7 is a dia-grammatic section showing how flaps may be applied to envelopes or cards for filing purposes.

There may be provided a sheet 10 which may be made of cardboard or paper or any other suitable material. Referring to Figs. 1 and 2, perforations 11 to 20 are oppositely arranged in parallel spaced rows preferably near the edges of the sheet. Parallel rows of cords between the perforations may be provided in suitable manners. As illustrated a short distance from the perforation 11 is placed the looped end 21 of a cord 22. The cord 22 is passed across the sheet 10 and through the perforation 12 and back at 23 on the other side of the sheet and through the perforation 11 and through the loop 21. The cord is adjusted to required tension and then passes back through the perforation 11 to the front of the sheet. The cord then passes downward at 24, and through the perforation 13, across the sheet 10 at 25, and through the perforation 14 and back on the other side of the sheet

10 at 26, through the perforation 13 and downwardly at 27. This method of lacing may be continued until the cord has passed back and forth across both sides of the sheet through all the 5 perforations, when the free end after passing at 67 from the perforation 20 to the perforation 19 is tied in a fastening knot 28 to the downward cord 30. Thus there may be provided a series of parallel cords crossing the sheet at suitable 10 intervals which may be somewhat less widely separated than the width of the specific envelopes, etc., to be filed.

In Figs. 3 and 4 is illustrated another method of lacing the cords on the sheet. Perforations 15 31 to 42 are oppositely arranged in parallel spaced rows preferably near the edges of the sheet. A loop 43 on the end of a cord 45 is placed a short distance from the perforation 32 and the cord 45 is passed across the sheet 10 and through the 20 perforation 31 and back at 44 on the other side of the sheet and through the perforation 32 and through the loop 43. The cord is adjusted to the required tension and passed back through the perforation 32 and down along 46 and through the 25 perforation 34 and across the sheet 10 at 48, through the perforation 33 and across the sheet along 47. The cord then goes under the downward cord 46 and down to the perforation 36 and continuing in like manner to perforations 40 or 42 as desired where the end of the cord is fastened in any suitable manner. If a pocket is used at the bottom of the sheet the cord 62—63 need not be used.

The perforations may be reinforced in any suitable way if desired.

To facilitate lacing of the cord on the sheet slits 50 may be made from the perforations to the edge of the sheet so that the cord may be drawn into the perforations through the slits, as indicated in Figs. 1 and 2.

Across the bottom of the sheet 10 on one or both sides a pocket 51 may be attached in any suitable manner, such as by pasting at the edges or the like.

Over any cord between oppositely disposed perforations such as 45 for instance in Figs. 3 and 5, the flap 52 of an envelope 53 may be folded so that the cord 45 lies between the flap 52 and the envelope 53 to hold the envelope in place. To hold the bottom of the envelope 53 it may be passed under the next lower cord 48 which passes between the perforations 33 and 34 on the same side of the sheet 10. Over the cord 48 the flap 54 of the adjacent envelope 55 may be folded so that the cord 48 lies between the flap 54 and the envelope 55. Since the bottom of the envelope 53 has been passed under the cord 48 the top of the envelope 55 and its flap enfolded the cord 48 overlaps the bottom of the envelope 53, and in like manner the bottom of the envelope 55 can be passed under the cord which passes be-

tween the perforations 35 and 36, and the top of the succeeding envelope with its flap and the cord between the perforations 35 and 36, will 5 overlite the bottom of the envelope 55. Each of the envelopes supported by the succeeding cords may in like manner overlite the envelope supported by the cord next above until the bottom envelope is put in place, when the bottom of the bottom envelope 65 (Figs. 4 and 5) may be placed inside the pocket 51 when it is present, to hold 10 all of the envelopes snugly together by pressure and to prevent movement of the envelopes away from the cords when the sheet is handled while the envelopes are in place. A snug, close, flat mounting for the envelopes is thus obtained.

The pocket 51 is not essential; when it is omitted or the sheet is not fully used, the lowermost envelope in place on the sheet may be held from flapping by the lowermost cord and for the purpose, when desired, the lowermost cord may be 15 arranged as near the bottom of the sheet as desired.

The sheet may be wide to allow a portion to be used as a binding strip, with or without a crease, or a separate binding strip 66 may be attached as illustrated, in any suitable way, such as by the use of binder tape 67, or other suitable material flexible enough to allow the sheet to be readily turned. Binding holes 68 may be provided. Binding is not essential but separate sheets alone, with perforations near each edge may be used.

The cord need not be tied to the sheet, but may be passed through the holes or slots at one edge of the sheet and back to the other edge of the sheet on both sides of the sheet, where the two ends may be fastened by staples, clips, or other suitable means 69 passing through the sheet and the cord or tape 70 on each side of the sheet, as illustrated in Fig. 6. The ends 71 and 72 of the tape may extend beyond and be fastened to the binding strip. As illustrated in Fig. 6 one means of attaching the binding strip to the sheet is to pass the end 71 of the upper tape under the binding strip 66 and fasten it to the under side of the strip. The end 72 of the under tape is passed over the binding strip 66 and fastened to its upper side at a point just above the point where the upper end 71 is fastened.

Cords may be tied into loops through each pair of perforations. Or sheets with perforations at one edge only may be used when the cord will be attached at the other edge as illustrated in Fig. 6 for instance.

The number of perforations may be increased to increase the number of envelopes to be mounted on each sheet, or fewer or a single cord may be used. The position of the perforations may be different, as where they may be placed along the top and bottom of the sheet to hold longer envelopes. In this form the pocket 51 may be placed preferably on the outer side of the sheet 10 instead of on the bottom as illustrated in Fig. 1.

The usual envelope may have an integral flap as illustrated in Fig. 3 but the invention may be adapted to envelopes in which the flap has been sealed or has not been preserved or to cards or other material not provided with flaps. As shown

diagrammatically in Fig. 7, to the envelope 73 may be fastened a flap 74 similar to an envelope flap by any suitable means, such for instance as pasting or clipping. These flaps, attached to the portion of the card or material not to be displayed, may be single flaps which may extend throughout the lengths of the cards, etc., or one or more narrower flaps may be fastened at intervals along their lengths. The terms "flaps" and "envelopes" are used in the claims to embrace all such arrangements.

It will be understood that the term "cord" is used to indicate any suitable device which may be of cotton, etc., or a metallic wire or a flat tape if desired, and the cord may be flexible or rigid as desired, and to the extent desired.

The proportions and shape, etc., of the sheet, the number, spacing, etc., of the cords, and the material etc., is not essential to the present invention, which may be embodied in other forms.

I claim as my invention:

1. A sheet for filing envelopes provided with flaps, a plurality of parallel cords on the sheet, an upper cord being adapted to pass between an envelope and its flap and the next lower cord adapted to pass over the edge of the envelope remote from the flap and also to pass between a second overlying envelope and its flap, and a pocket on the sheet for enclosing the edge of the lowermost envelope remote from its flap.

2. A sheet for filing envelopes provided with flaps, a plurality of parallel cords on the sheet, an upper cord being adapted to pass between an envelope and its flap and the next lower cord adapted to pass over the edge of the envelope remote from the flap and also to pass between a second overlying envelope and its flap.

3. A mounting for envelopes provided with flaps comprising a sheet having pairs of opposite perforations thereon, one or more cords each passing through the pairs of perforations and adapted to pass under the envelope flaps, and a pocket on the bottom of the sheet adapted to receive the edge of an envelope remote from its flap.

4. A mounting comprising a sheet having perforations near each side margin of the sheet, cord laced through the perforations, and a pocket at the bottom of the sheet.

5. A sheet for filing envelopes provided with flaps having perforations at spaced intervals on one edge of the sheet, and a plurality of cords on the sheet each adapted to pass through one of the perforations and to be fastened at the opposite edge of the sheet, and each cord adapted to pass between an envelope and its flap and over an adjacent envelope.

6. A sheet for filing envelopes provided with flaps, a plurality of parallel cords extending across the sheet and fastened near one edge of the sheet, the ends of the cords being fastened to a separate binder strip.

7. A sheet for filing envelopes provided with flaps having at spaced intervals on the sheet oppositely arranged perforations with slits from the perforations to the edge of the sheet through which a cord may be drawn, and a cord passing through the perforations adapted to be placed between the envelopes and their flaps.

ARTHUR C. SHORT.
